CLAIM

The ornamental design for a shoe outsole, as shown and described.

DESCRIPTION

FIG. 1 is a front perspective view of a shoe outsole showing my new design;

FIG. 2 is a rear perspective view thereof;

FIG. 3 is a bottom view thereof;

FIG. 4 is a rear perspective view thereof;

FIG. 5 is an enlarged view of the claimed region in FIG. 2, shown in isolation from the remainder of the shoe for the purpose of clarity;

FIG. 6 is an enlarged view of the claimed region in FIG. 3, shown in isolation from the remainder of the shoe for the purpose of clarity;

FIG. 7 is an enlarged view of the claimed region in FIG. 4, shown in isolation from the remainder of the shoe for the purpose of clarity;

FIG. 8 is a side view thereof; and,

FIG. 9 is a front view thereof.

The broken lines immediately adjacent to the shaded area define the bounds of the claimed design and form no part thereof. The broken lines showing the remainder of the shoe represent unclaimed subject matter and form no part of the claimed design.
